Attorney.

UNITED STATES PATENT OFFICE.

TAYLOR L. MILLER, OF CHEYENNE, OKLAHOMA.

OVERALL-SUSPENDER BUCKLE.

1,358,384.

Specification of Letters Patent. Patented Nov. 9, 1920.

Application filed August 3, 1920. Serial No. 400,911.

To all whom it may concern:

Be it known that I, TAYLOR L. MILLER, a citizen of the United States, residing at Cheyenne, in the county of Roger Mills and 5 State of Oklahoma, have invented certain new and useful Improvements in Overall-Suspender Buckles, of which the following is a specification.

My invention relates to buckles for over-10 all suspenders.

My object is to provide a device of this character of simple, cheap and durable construction and one in which the loop can be most easily attached to or detached from 15 the buckle.

The invention consists in certain novel features of construction and arrangement of parts, as will be hereinafter described and claimed, reference being had to the accompanying drawings, in which:—

Figure 1 is a plan view of my improved buckle in operative position on a suspender strap.

Fig. 2 shows the method of connecting or 25 disconnecting the buckle and loop.

Fig. 3 shows a lower edge view of the buckle with the tooth bar in the position it occupies when the suspender strap is being withdrawn, the loop being omitted for clear-30 ness; and

Fig. 4 is a perspective view of the buckle plate, with the difference in the position of the two sleeves thereof somewhat accentuated.

The numeral 1 indicates the buckle plate 35 having the turned down sides 2 which support the tooth bar 3 of the buckle in an ordinary and well known manner. Any other ordinary or preferred means for gripping 40 the suspender strap may be employed if desired, as that feature does not form any part of my invention.

The plate 1 has a cutaway portion 4, central of its lower edge, which forms said edge 45 into two sections spaced from each other, and which in turn are bent to form two sleeves 5 not in alinement with each other but lying in spaced parallel planes.

The loop 6 is formed of a piece of spring 50 metal bent upon itself and terminating at its upper end in the outwardly extending sections 7 which are received into the sleeves 5.

The feature of the invention to which special attention is called is the arrangement of 55 the sleeves 5 in vertical parallel planes slightly spaced from each other instead of being in the same plane as is ordinary.

From Fig. 2 of the drawings it will be seen that this arrangement permits the outwardly turned ends 7 of the loop to be easily entered into the sleeve 5 or removed therefrom, as would not be the case if the sleeves 5 were in alinement with each other.

When the ends 7 of the loop are received 60 into the sleeves 5, the upper end of the loop immediately adjacent said ends is received into the cutaway portion 4 of the plate 1.

The sleeves 5 are of larger internal diameter than the diameter of the ends 7 of the 65 loop, whereby said ends have sufficient lateral play in said sleeves to permit the loop to hang in the same plane with the plate 1 and with the suspender strap, or in a plane 70 parallel therewith.

The sleeves 5 may be provided at their 75 inner ends and on their inner sides with the ordinary sleeve shoulders 8 if desired, or the shoulders may be entirely omitted. In Figs. 2 and 3 of the drawings I have shown 80 the sleeves provided with these shoulders, while in Fig. 4 they are omitted.

When the sides of the loop 6 are pressed toward each other, as partially illustrated in Fig. 2, one of the ends 7 of the loop is 85 withdrawn from its coöperating sleeve 5, and when one end is withdrawn the other can be easily withdrawn: while entering one of the ends 7 in its appropriate loop and then springing the two sides of the loop toward each other, the other end of the loop 90 can be easily entered into the other sleeve.

Having now described my invention, what I claim as new and desire to secure by Letters Patent is:—

1. In a device of the character described, a buckle plate having spaced sleeves disposed at an angle thereto and out of alinement with each other; and a spring loop having outwardly bent ends adapted to be received 100 into said sleeves at their inner ends.

2. In a device of the character described, a buckle plate having at its lower edge a pair of sleeves spaced from each other at their inner ends and disposed in parallel planes 105 at an angle to the plate; and a spring loop

received between said spaced sleeves and terminating in outwardly bent ends adapted to extend into said sleeves.

3. In a device of the character described, a buckle plate having at its lower edge a pair of spaced sleeves lying in the same horizontal plane and disposed in vertical parallel

planes; and a spring loop adapted to be received at its upper end between said spaced sleeves and terminating at its upper end in 10 outwardly bent sections adapted to extend into said sleeves.

In testimony whereof I affix my signature.
TAYLOR L. MILLER.
